UNITED STATES PATENT OFFICE.

RICHARD GERNER, OF PORT CLINTON, OHIO.

BOLSTER-STAKE FOR VEHICLES.

SPECIFICATION forming part of Letters Patent No. 313,199, dated March 3, 1885.

Application filed September 27, 1884. (No model.)

To all whom it may concern:

Be it known that I, RICHARD GERNER, of Port Clinton, in the county of Ottawa and State of Ohio, have invented certain new and 5 useful Improvements in Bolster - Stakes for Vehicles; and I do hereby declare that the following is a full, clear, and exact description of the invention, which will enable others skilled in the art to which it appertains to make and 10 use the same, reference being had to the accompanying drawings, which form a part of this specification, and in which—

Figure 1 is a perspective view of one of my improved bolster - stakes for vehicles, showing the same attached to the end of the bolster in position for operation. Fig. 2 is a side view of the same. Fig. 3 is a vertical transverse sectional view of the same, and Fig. 4 is a perspective view showing the lower end 20 of my improved bolster-stake detached.

The same letters refer to the same parts in all the figures.

This invention relates to bolster-stakes for vehicles; and it has for its object to provide 25 a cast-metal stake which shall be simple in construction, durable, easily applied, and neat in appearance, and which shall serve as a brace for the bolster, dispensing with any necessity of a transverse bolt for the end of the 30 latter, and which shall form a strong and convenient socket for the insertion of extension-stakes, when required, without necessity for any of the clumsy contrivances now generally used for the purpose of holding such extension-pieces when required.

With these ends in view the invention consists in the improved construction of such stakes, which will be hereinafter fully described, and particularly pointed out in the 40 claim.

In the drawings hereto annexed, A designates the body of my improved bolster-stake, which consists of a comparatively flat and narrow vertical plate, the side or face of which 45 is provided with flanges B B, converging at or near the center, as shown at C. The lower ends of the said flanges are integral with the horizontal base-plate D, and their upper ends are connected at some distance from the top 50 of the standard by a solid portion, E, having

a re-enforcing flange, F. The upper ends of the flanges B B form, with the ring or solid portion E, a socket, G, the bottom of which is at the point where the said ribs or flanges B B converge. This socket is necessarily 55 and naturally of a somewhat tapering shape, which is especially adapted for the insertion and secure retention of an extension-stake, H, the lower end of which is simply pointed, so as to enable it to readily enter the 60 said socket. The body A of the stake is formed or provided with a bolt, I, extending a sufficient distance below the base-plate D to enable the said bolt to pass vertically through the end of a bolster, J, and receive the nut 65 K, whereby the stake is secured in position upon the said bolster. The outer corners of the base-plate are provided with downwardly-extending lugs or lips L L, fitting against the sides of the bolster, thereby preventing 70 the latter from splitting or spreading, adding to the security of the attachment of the stake, increasing the strength of the latter, and dispensing with the necessity of the transverse bolt usually inserted through the end of the 75 bolster in order to prevent it from splitting.

The operation and advantages of this invention will be readily understood from the foregoing description, taken in connection with the drawings hereto annexed.

My improved bolster-stake is complete in a single piece or casting, and but a single nut is needed for its attachment to the bolster. It is light and durable, being greatly strengthened by the ribs or flanges B B, which perform the additional function of forming the socket for the insertion of an extension-stake when required.

If desired, the stake may be additionally secured by nails or a rivet driven through the 90 lugs L L, which may be provided with perforations for this purpose.

The device is easily applied to any ordinary bolster, and it is neat and inexpensive.

I am aware that wagon stakes or standards 95 have been made with a socket for the reception of an extension-stake, and having flanges at their lower ends clamping the ends and sides of the bolster; and I do not claim such construction, broadly; but

I claim—

The bolster-stake consisting of the body-plate A, having flanges B B, converging at C, and formed into a socket, G, having re-enforcing rib E, and the base-plate D, having lugs L and nutted bolt I K, in combination with the bolster J and extension-stake H, as and for the purpose shown and set forth.

In testimony that I claim the foregoing as my own I have hereunto affixed my signature in presence of two witnesses.

RICHARD GERNER.
